UNITED STATES PATENT OFFICE.

CHARLES W. BRAY, OF PITTSBURG, PENNSYLVANIA, ASSIGNOR TO AMERICAN SHEET & TIN PLATE COMPANY, OF PITTSBURG, PENNSYLVANIA, A CORPORATION OF NEW JERSEY.

METHOD OF TREATING PACKS.

No. 874,732.

Specification of Letters Patent.

Patented Dec. 24, 1907

Application filed March 18, 1907. Serial No. 362,888.

To all whom it may concern:

Be it known that I, CHARLES W. BRAY, of Pittsburgh, Allegheny county, Pennsylvania, have invented a new and useful Method of 5 Treating Packs, of which the following is a full, clear, and exact description, reference being had to the accompanying drawings, forming part of this specification, in which—

Figure 1 is a side elevation showing apparatus for carrying out my invention; and Fig. 2 is a plan view of the same.

My invention relates to the rolling of sheet metal in packs, and it is designed to provide a new and improved method of opening or 15 loosening the sheets of a rolled pack.

In the manufacture of sheet metal, especially by what is known as the continuous mill system, wherein the packs pass through successive sets of rolls, difficulty has been experienced in excessive sticking of the sheets of the pack causing a considerable loss in scrap by reason of torn or injured sheets which cannot be pulled apart.

My invention is designed to reduce this 25 difficulty of sticking of the packs, and it consists in applying a cooling fluid to one or both faces of the heated pack. The step is preferably applied between successive rolling operations, though it may be applied at any desirable time through the process while the 30 pack is heated.

In the drawings, in which I show one form of apparatus for carrying out my invention, 2, 2 and 3, 3 indicate successive sets of rolls of 35 a tandem mill for rolling sheets. Between these sets of rolls I show a chain table having inner angled bar rests 4, 4, and outer adjustable side guides 5, 5. Between the supports and guides 4 and 5 are provided the roller 40 chains 6 having rollers 7, which project above the level of the supports 4 and move over the end sprocket wheels 8, 8. These sprocket wheels are shown as mounted upon shafts 9 carried in bearings 10 and 11, of which the 45 bearing 11 is shown as adjustable to regulate the tension of the chains. These bearings are shown as mounted in side casings 12, which may rest upon suitable transverse supports. The shaft 9 may be driven by a 50 sprocket wheel 13 and chain 14 extending from a driven shaft 15.

In order to apply the cooling fluid to the pack, I preferably employ transverse spray pipes 16 leading from a supply pipe 17. 55 These pipes are preferably perforated on

their lower sides, and spray streams of water upon the top of the packs as it is fed along over the chain table. I also preferably use similar pipes 18 beneath chains, these pipes having upper perforations to spray the lower 60 face of the pack.

The action of the cooling fluid or liquid is to suddenly chill the outer plate or portions thereof, and thus contract it relative to the next plate, causing a movement of one plate 65 upon the other. This loosens the plates and largely prevents their sticking while enabling the plate to be fed along. The operation is thus carried out without any delay or complication in the apparatus other than the mere 70 addition of pipes for supplying the cooling liquid or fluid. In carrying out the process, the hot pack passes through the reducing rolls 2, and as it passes over the chain table it is sprayed on the top and bottom, and the 75 sheets thus loosened and drawn over each other. The pack thus feeds forwardly into the next reducing pair of rolls 3, 3, where a further reduction may be made as the amount of water applied is preferably not 80 sufficient to chill the pack below a rolling temperature.

The advantages of my invention will be apparent to those skilled in the art. The application of cooling fluid causes unequal 85 expansion and contraction of the various plates or sheets of the pack, thus taking advantage of natural forces to loosen the sheets from each other.

The process may be used in connection 90 with the mechanical opener or without it; the fluid used may be either a gaseous fluid such as chilled air, or a liquid such as water, and many changes may be made in the form and arrangement of the apparatus without 95 departing from my invention.

I claim:—

1. The method of opening or loosening the sheets or plates of a pack in which the said sheets or plates stick together, which consists in applying a cooling fluid to the pack while heated; substantially as described.

2. The method of loosening sheets or plates of a pack in which the said sheets or plates stick together, which consists in feeding the pack forwardly while heated, and at the same time applying a cooling fluid thereto; substantially as described.

3. The method of opening or loosening sheets or plates of a pack, in which said

110

sheets or plates stick together, which consists in applying a cooling fluid to the top and bottom faces of the pack while heated; substantially as described.

5. 4. The method of opening or loosening the sheets or plates of a pack in which the said sheets or plates stick together, which consists in applying separate streams of cooling fluid to the pack while heated; substantially as described.

5. In the manufacture of sheet metal, the

method which consists in rolling the heated pack, and then subjecting said heated pack to the action of a cooling fluid, thereby loosening the sheets of the pack from each other; 15 substantially as described.

In testimony whereof, I have hereunto set my hand.

C. W. BRAY.
